UNITED STATES PATENT OFFICE.

REUBEN B. THOMPSON, OF COHOES, NEW YORK, ASSIGNOR TO UNION SPECIAL MACHINE COMPANY, OF CHICAGO, ILLINOIS, A CORPORATION OF ILLINOIS.

GARMENT.

1,169,581.

Specification of Letters Patent. Patented Jan. 25, 1916.

Application filed January 8, 1911. Serial No. 801,657.

To all whom it may concern:

Be it known that I, REUBEN B. THOMPSON, a citizen of the United States, residing at Cohoes, in the county of Albany, State of New York, have invented certain new and useful Improvements in Garments, of which the following is a description, reference being had to the accompanying drawing and the letters and figures of reference 10 marked thereon.

The invention relates to new and useful improvements in garments, and more especially to garments which are made of knitted fabric.

15 Prior to my invention it has been the common practice to secure a knitted collaret to a knitted garment by means of cross stitching which united the collaret and body garment with their edges abutted or slightly overlapped. It has been found however, that garments constructed in this manner 20 are liable to stretch at the neck and become very much distorted, which greatly injures the wearing quality of the garment.

25 An object of my invention is to provide means for uniting the collaret to the body garment by cross stitching, which securely unites these parts, and to provide means for preventing the undue stretching of the finished garment as above referred to.

30 A further object of the invention is to provide means for uniting the shoulder seam and to also provide means for preventing the undue stretching of the shoulder seam, so that the entire garment across 35 the shoulders thereof and about the neck, will permanently retain its original form and thereby the wearing qualities of the garment greatly increased.

40 In the drawings which show by way of illustration one embodiment of the invention: Figure 1 is a front view showing the upper portion of a garment having my invention applied thereto; Fig. 2 is an enlarged detail view from the wrong side 45 of the garment, showing the manner of joining the collaret to the body garment; Fig. 3 is a similar view from the front of the garment; Fig. 4 is a diagrammatic view 50 through the seam for uniting the parts.

55 In the drawings I have shown a body garment 1 to which is attached a collaret 2 by a line of stitching 3, which extends entirely around the neck of the garment. In uniting the body garment to the collaret,

the edges thereof are slightly overlapped, as shown in Figs. 2 and 3, and a tape 4 is laid on said overlapped edges on the inner face of the garment. The body garment, collaret, and tape are secured together as 60 herein shown, by three parallel lines of stitching 7, 8, and 9. The line of stitching 7 passes solely through the collaret, while the line of stitching 9 passes solely through the body garment. The line of stitching 8 65 passes centrally through the tape 4 and through the overlapped edges of the body garment, and collaret. The lines of stitching are joined together and the tape covered and concealed by covering threads 5 70 and 6, which are laid back and forth underneath the stitches 7, 8, and 9. The line of stitching 7, 8, and 9 are united and secured by the looper thread 10 which also joins all the needle loops and extends from 75 one row to the other so that the raw edges of the collaret and body garment are covered and concealed by said looper thread. This tape which is formed as a part of the seam for joining the collaret and body garment, is formed of inelastic material and will thereby prevent the undue stretching 80 of the collaret and body garment which are formed of knit material. I may also use my improved seam for joining the collaret 85 and body garment for joining the back and front portions of the shoulders. The back portion of the garment 11 is secured to the front portion of the garment by the seam as above described, as clearly shown in Fig. 90 1. This seam 3 including the tape, extends from the seam joining the sleeves to the garment, to the seam joining the collaret to the body garment where it is joined thereto.

95 It will thus be seen that in my improved garment an inelastic tape extends substantially from one arm across the shoulder and around the neck of the garment, and then across the other shoulder to the other arm so that the entire upper part of the 100 garment is prevented from undue stretching. In the making of the seam herein shown, and described, I prefer of course, to use a three needle sewing machine wherein the covering threads are simultaneously 105 laid back and forth in front of the needles and the tape is fed underneath the same so that the parts of the garment and the tape are simultaneously joined and covered.

110 It is obvious that minor changes in the

details of construction and the arrangement of parts may be made without departing from the spirit of my invention.

Having thus particularly described my invention, what I claim as new and desire to secure by Letters Patent, is:—

A garment comprising sections formed of knitted material, said sections having overlapping meeting edges, an inelastic tape covering said overlapping edges on one face of the garment, a line of stitching passing centrally through the tape and said overlapping edges, a line of stitching at each

side of said central line of stitching and passing through the knitted sections and covering threads joining all of said lines of stitching, said covering threads lying on the outer face of the tape and covering the same and on the opposite face of the garment.

In testimony whereof I affix my signature, in presence of two witnesses.

REUBEN B. THOMPSON.
